FENCE STRUCTURE

Jolly L. Morris, Ellwood City, Pa.

Application February 11, 1950, Serial No. 143,687

4 Claims. (Cl. 256—73)

1

This invention relates to fence structures and more particularly to a fence structure which is adapted to be set up on varying contour with equal facility.

It is frequently desirable to have a fence structure which can be moved from place to place and set up quickly and firmly without regard to the contour of the land. Fences of a flexible and portable character have heretofore been proposed but in general they have not been entirely satisfactory. In many proposed fences of a flexible character suitable for use on uneven terrain it is extremely difficult to install them over such terrain and maintain symmetry of outline with any degree of success. Moreover, in every case it is necessary to anchor at least one post in the ground at the end of each panel of such fences. In such fences as have been heretofore proposed the spaced relationship between horizontal fence rails varies with the angularity or unevenness of the terrain thus destroying the symmetry of the fence and making it less pleasing to the eye.

The fence structure of this invention is readily adaptable for erection on any terrain regardless of its unevenness and is at the same time readily portable to a certain extent. This fence structure may be installed with a minimum of effort and expense. The fact that the fence posts next to the corner posts are not anchored in the ground when the fence is installed makes it easy to move the fence vertically for mowing or weeding in the fence row as for example between an anchored corner post and an adjacent unanchored post.

In general, the fence structure of this invention comprises the combination of spaced apart anchor posts adapted to be firmly fastened to the ground, at least one intervening post between the spaced apart anchor posts and having a base member adapted to rest upon the surface of the ground, and a fence panel pivotally connected between each two adjacent posts for movement in a vertical plane. Preferably the fence panel is made up of an upper and lower railing member hinged to the posts and carrying spaced apart upright members removably mounted thereon.

The structure of this invention will be more clearly understood by referring to the accompanying drawings in which:

Figure 1 is a side elevation of a fence structure according to this invention.

Figure 2 is a top plan view of a corner of fence structure according to this invention.

2

Figure 3 is a side elevation of a single fence panel and posts according to this invention.

Figure 4 is a perspective view of a segment of fence structure.

5 Figure 5 is a top plan view of a composite rail for use in connection with the invention.

Figure 6 is a top plan view of a second embodiment of a composite rail.

Referring to the drawings there is illustrated 10 an anchoring post 10 which is driven into the ground. An upper railing 11 and a lower railing 12 are connected at one end to the anchoring post 10 by hinges 13. The other end of the two railings 11 and 12 are hinged to a second 15 post 15 which is not anchored in the ground but rests upon a ground plate 16. Upright members or palings 17 are inserted in spaced apart openings 18 in the upper railing 11 and in similar spaced apart openings 19 in the lower railing 12. A tapered pin 20 is inserted in a tapered hole 21 in the lower railing 12 and a corresponding tapered hole 22 in the upright member 17. The upright member 17 and railings 11 and 12 thereby form a complete removable fence panel 25 hingedly attached to the posts.

The openings 18 and 19 in the upper and lower railings 11 and 12 may be cut into a solid piece of wood as shown in Figure 3. They may also be formed by making up a composite railing of 30 two pieces each of which has approximately one half of the opening inlets into it as shown in Figure 5. A similar structure is shown in Figure 6 in which the opening is inlets into but one piece of the two piece composite rail. These 35 openings 18 and 19 are preferably made slightly longer than the width of the upright member 17 as shown in Figure 4 to permit the upright member to rest therein at an angle other than perpendicular. Preferably the openings 18 and 19 40 are made to fit firmly upon the side of the uprights 17.

The erection and removal of the fence can be facilitated by using a hinge 13 having a removable pintle 13a. 45 The arrangement of railings and upright members in which the upright is pivoted in the lower railing but not in the upper railing permits the fence to be more symmetrically arranged than is the case where the upright members are pivoted to both upper and lower railings. Where the upright members are pivoted to both railings the two railings approach each other as the angularity of the fence slopes either upwardly or downwardly thereby destroying the general symmetrical appearance of the fence and making it 50

55

less pleasing in appearance by reason of the change of spacing between the rails with changes in terrain.

In a preferred form of installation all corner posts are anchored in the ground and each adjacent post rests on a ground plate so as to be unanchored. All other posts in the fence structure are anchored in the ground thereby making a very rigid installation yet permitting clear mowing or weeding in and around the fence corners.

It is readily apparent from the above description and the drawings that the fence structure of this invention is quickly and easily assembled on a surface of relatively rough contour without special tools or equipment. This fence structure is simple, easily fabricated and therefore inexpensive and fulfills a long-felt need for a quickly and easily erected fence of great flexibility and strength.

While there is illustrated and described a preferred embodiment of this invention it will be understood that it may be otherwise embodied within the scope of the following claims.

I claim:

1. In a fence structure, the combination of spaced apart anchor posts adapted to be firmly fastened to the ground, at least one intervening post between the spaced apart anchor posts and having a base member adapted to rest upon the surface of the ground, an upper and lower railing member pivotally connected between each two adjacent posts for movement in a vertical plane, spaced apart openings in said railings adapted to receive upright members extending between said railings and removable fastening means cooperating with the lower railing and each upright member to hold each upright member in position in the upper and lower railings

10 said upright members being free to move vertically in the openings in the upper railings.

2. In a fence structure, the combination of spaced apart anchor posts adapted to be firmly fastened to the ground, at least one intervening post between the spaced apart anchor posts and having a ground plate on the lower end thereof adapted to rest upon the surface of the ground, an upper and lower railing member connected by a hinge at each end thereof to each two adjacent posts, spaced apart openings in said railings adapted to receive upright members extending between said railings and removable fastening means cooperating with the lower railing and each upright member to hold each upright member in position in said railings said upright members being free to move vertically in the openings in the upper railing.

20 3. A fence structure as claimed in claim 2 in which the removable fastening means includes a tapered pin cooperating with a tapered opening extending through the lower railing and each upright member.

25 4. A fence structure as claimed in claim 2 in which the leaves of each hinge are fastened to a post and to the lower side of a railing and are connected by a removable pintle and the upper side of the railing above the hinge leaf is relieved to permit free rotation of the railing in the vertical plane about the hinge pintle.
